[57] CLAIM

The ornamental design for a collapsible cargo container, as shown and described.

DESCRIPTION

FIG. 1 is a top perspective view of a collapsible cargo container showing my new design;

FIG. 2 is an exploded perspective view thereof;

FIG. 3 is an enlarged, fragmentary sectional view of one of the bolts of FIG. 1;

FIG. 4 is a sectional view taken along line 4—4 of FIG. 2;

FIG. 5 is a sectional view taken along line 5—5 of FIG. 1; and

FIG. 6 is an enlarged, exploded perspective view of a hinged corner typical of all corners thereof.
